APPARATUS FOR REMOVING SURPLUS INSULATION FROM ARMATURE CORES

Application filed January 6, 1930. Serial No. 418,975.

This invention relates to the manufacture of armatures for dynamo electric machines and more especially to the type of manufacture which includes the steps of insulating a 5 slotted armature core with a lining of sheet insulating material portions of which may over-lie the peripheries of armature core teeth as well as line the core slots, of winding wire into the core slots thus holding the 10 slot insulation in position, and then of removing the surplus insulation which over-lies the peripheries of the armature core teeth.

One of the objects of the present invention is to provide apparatus for removing the surplus insulation at the peripheries of the core teeth, and in order to accomplish this object the present invention provides a 15 work holder for rotatably supporting an armature core and a pair of wire bristle brushes rotating in opposite directions while simultaneously engaging the core which may be rotated while being engaged by the positively rotating wire bristle brushes.

Further objects and advantages of the present invention will be apparent from the following description, reference being had to the accompanying drawings wherein a preferred embodiment of one form of the 20 present invention is clearly shown.

In the drawings:

Fig. 1 is a front elevation of a machine embodying the present invention. The part of Fig. 1 shown in section is taken on the 25 section line 1—1 of Fig. 2.

Fig. 2 is a side elevation of the machine shown in Fig. 1. The parts shown in section are taken respectively on the section lines 2—2, 2a—2a and 2b—2b of Fig. 1.

Fig. 3 is a plan view partly in section taken on the line 3—3 of Fig. 1.

Fig. 4 is a fragmentary sectional view taken on the line 4—4 of Fig. 2.

Fig. 5 is a sectional view on the line 5—5 of Fig. 2.

Fig. 6 is a sectional view on the line 6—6 of Fig. 5.

The supporting frame of the apparatus comprises a table top 20 attached to channel bars 21 in turn attached to leg frames 22 having channel cross bars 23 which support two of those shelves 24. The table top 20 provides dove-tail ways 30 and 31 which guide for horizontal sliding movement bearing brackets 32 and 33 respectively in which shafts 34 and 35 respectively are journaled. The shafts 34 and 35 support and drive rotatable wire bristle brushes 36 and 37. The 50 brushes 36 and 37 are driven in opposite directions as indicated by arrows 38 and 39 respectively by electric motors 40 and 41 respectively. To the shafts 40a and 41a of these motors are attached pulleys 42 and 43 respectively connected by belts 44 and 45 respectively with pulleys 46 and 47 respectively attached to the shafts 34 and 35 respectively. The motors 40 and 41 are mounted respectively on bases 50 and 51 hingedly connected at 52 and 53 respectively with the shelves 24. Each of the belts 44 and 45 may 55 be tightened by a belt tightening device co-operating respectively with the motor bases. For example, the base 50 may be moved in a 60 counterclockwise direction about its pivot 52 in order to tighten the belt 44 by turning the nuts 54 and 56 down along a bolt 58 attached to a rod 60 having its ends journaled in brackets 62 attached to the shelf 24. The belt 45 is 65 tightened in a similar manner by screwing nuts 55 and 57 down along a bolt 59 attached at its lower end to a cross bolt 61 journaled 70 at its end in bracket 63.

The work holder comprises a block 70 providing a bearing for a rod 71 attached to a member 72 providing a socket for a recess 73 for receiving one end of an armature shaft 74 supporting a core 75 into which windings 76 have been wound. The holder member 72 provides a cup-shaped head 77 for receiving the windings at 76a which over-lie the inner 80 85 90 95

end of the core and which surround the shaft 74 as viewed in Fig. 3. Normally the head portion 77 is located between the brushes 36 and 37 where it will be readily accessible 5 for receiving an armature core to be operated on by the machine. The member 72 is held in this position nearest the front of the machine by a spring 78 located between the work holder block 70 and a thrust bearing 79 10 surrounding the shank of the work holder member 72 and bearing against a shoulder 80 thereof. The outward movement of the work holder 72 is limited by a washer 81, attached to the rod 71 by a nut 82, striking against the 15 work holder block 70.

In order to strip or remove surplus insulation from the periphery of the armature core, the operator grasps one end of the armature, for example, end 74a shown in Fig. 3, 20 and inserts end 74b in the socket 73 of the work holder member 72, and pushes the armature and the work holder toward the machine and into the position shown in Fig. 3. While the brushes are rotating the operator turns the armature core so that all portions thereof will be moved into contact with the bristles of the rotating brushes which soon wear away the paper insulation leaving the core teeth bare as shown in Fig. 3. When 25 the operator removes the armature from the work holder, the spring 78 is permitted to move the work holder to a forward position between the brushes 36 and 37.

The brushes being of the same diameter 30 and rotating at substantially the same speed there will be substantially no tendency for the armature core to be rotated due to contact with the brushes; therefore the core may be easily rotated manually. It will be understood that the brushes are originally of 35 the same diameter and will remain equal in diameter until worn away since they wear away substantially at an equal rate. It is not intended by Fig. 3 to show that the brushes are of different diameters at the 40 same time. Fig. 3 shows that initially both brushes may have a diameter as large as the diameter of brush 37 in Fig. 3 and may wear down to a diameter as small as that of brush 45 36 shown in Fig. 3. As the brushes wear away it is necessary to move the brush bearing brackets 32 and 33 closer to the work holder block 70. As the devices for moving these brackets are alike only that device pertaining to bracket 32 will be described. 50 Bracket 32 provides a recess 90 for receiving the circular head 91 of a screw 92 which is threaded through a nut 93 carried by a stationary bracket 94 attached by screws 95 to the table 20. The head 91 of the screw 92 is retained by a plate 91a having a hole larger 55 in diameter than the body of the screw 92 and smaller than its head 91. This plate 91a is attached to the bracket 32 in any suitable manner. The screw 92 carries a hand wheel

96 by which the screw is turned in order to slide the bracket 32 along the way 30 of the table 20. After the bracket 32 has been located in the proper position to compensate for wear of the brush 36 it is clamped in this 70 position to the way 30 by turning the handle 100 of a screw 101 which is threaded into a portion of the bracket 32. The handle 100 bears against the bifurcated side extension 102 of a wedge 103 having a surface 104 75 which is tapering with respect to the surface 105 of the wedge which engages the surface 106 of the way 30. The tapering wedge surface 104 cooperates with a correspondingly tapering surface 107 of the bracket 32 which 80 is non-parallel with respect to the surface 106 of the way 30. It is apparent that by turning the handle 100 so that the screw 101 is threaded into the bracket 32 that the wedge 103 will be forced into gripping engagement 85 with the surfaces 106 and 107 of the way 30 and the bracket 32 respectively. As a further precaution against accidental movement of the bracket 32 from the desired position of adjustment, the adjusting screw 92 90 is hindered from turning by the tightening of a clamping screw 110.

The brushes are enclosed by a suitable housing 130 shown in full line sectional views in Figs. 2 and 3 and as a phantom view by 95 dot and dash lines 130a in Fig. 1. The housing 130 provides a notch 131 through which the work holder may extend to receive the armature to be operated upon.

While the form of embodiment of the present invention as herein disclosed, constitutes a preferred form, it is to be understood that other forms might be adopted, all coming within the scope of the claims which follow.

What is claimed is as follows:

1. Apparatus for removing surplus insulation from an armature core comprising, in combination, a pair of parallel shafts rotatably supporting respectively a pair of wire bristle brushes, a pair of brackets each rotatably supporting the shaft, a work holder block located between the shaft brackets, a rod rotatably supported by the block and movable axially relative to the block, an armature receiving work holder attached to 100 said rod and means resiliently urging said work holder away from the work holder block into a position between the rotating brushes, and means for rotating the brushes simultaneously in opposite directions. 105

2. Apparatus for removing surplus insulation from an armature core comprising, in combination, a supporting frame, a table top, a pair of shaft bearing brackets supported by the table top and guided by ways provided 110 therein, said ways locating the brackets so that their bearings will always be in parallelism and guiding said brackets for movement in directions at right angles to the axes of said bearings, shafts supported by said 115

bearing brackets and each carrying a rotatable wire bristle brush, a work holder for rotatably supporting an armature core between said brushes, means for simultaneously rotating said brushes in opposite directions, devices for independently adjusting said bearing brackets along the table, and devices for clamping said bearing brackets to the table in adjusted position.

5 10 In testimony whereof we hereto affix our signatures.

ALVA W. PHELPS.
JOHN Q. HOLMES.
